DESIGN FOR A MUG

Harriet Hopkins Berne, Cincinnati, Ohio

Application February 16, 1945, Serial No. 118,004

Term of patent 7 years

(Cl. D44—9)

To all whom it may concern:

Be it known that I, Harriet Hopkins Berne, a citizen of the United States, residing at Cincinnati, in the county of Hamilton and State of Ohio, have invented a new, original, and ornamental Design for a Mug, of which the following is a specification, reference being had to the accompanying drawing, forming part thereof.

I claim:

The ornamental design for a mug, as shown.

HARRIET HOPKINS BERNE.
